UNITED STATES PATENT OFFICE.

FREDERICK R. STILL, OF DETROIT, MICHIGAN, ASSIGNOR TO AMERICAN BLOWER COMPANY, OF DETROIT, MICHIGAN, A CORPORATION OF MICHIGAN.

FAN WHEEL AND METHOD OF MAKING THE SAME

Application filed May 25, 1920. Serial No. 384,056.

To all whom it may concern:

Be it known that I, FREDERICK R. STILL, a citizen of the United States, residing at Detroit, in the county of Wayne and State 5 of Michigan, have invented certain new and useful Improvements in Fan Wheels and Methods of Making the Same, of which the following is a specification, reference being had therein to the accompanying drawings.

10 This invention relates to improvements in fan wheels and more especially to fan wheels of light build having long narrow blades and a large intake, and has for its object to provide an improved, simple, strong, light 15 fan wheel structure of this nature that can be produced at low cost.

Heretofore in the art, it has been proposed to secure the blades to the blade-supporting elements by riveting but such constructions 20 have proven unsatisfactory, the joints or connections between the parts soon shaking loose and rattling. Furthermore, riveting is especially unsuitable and is seriously objectionable in the manufacture of fan wheel 25 structures of light build of the character referred to because the shock incident to the usual riveting operation damages the parts, and affects the trueness of the wheel. A particularly important novel characteristic 30 of the present invention resides in the special method and means for securing the parts together, whereby a strong more durable structure is produced, the securing of the parts easily and more quickly effected without in- 35 jurious shock or pressure to the parts, riveting of the parts, as commonly practiced, being entirely avoided.

Other important novel features of the invention lie in the special formation of the 40 parts whereby they are adapted to be cheaply produced from stock materials, sheet metal stampings, pressed or drawn steel, and other metals, and the particular formation of the parts for reinforcement purposes 45 that results in a simple, light structure possessing great strength and rigidity, and in a considerable reduction in the cost of manufacture.

The invention, with other objects and ad- 50 vantages thereof, and the particular construction, combination and arrangement of parts comprising the same, will be understood from the following detailed description, when considered in connection with the 55 accompanying drawings forming part here-

of and illustrating embodiments of the invention.

In the drawings:

Figure 1 is a longitudinal section of a fan wheel or runner constructed in accordance 60 with the present invention.

Figure 2 is a detail view on an enlarged scale showing in side elevation a section of one of the end plates with some of the projecting end portions of the blades ar- 65 ranged in position prior to the welding operation, and other end portions of blades after the welding operation.

Figure 3 is a detailed section, on an en- 70 larged scale, of an end portion of one of the blades and one of the supporting plates, illustrating the relation of the parts prior to the welding operation.

Figure 4 is a view similar to Figure 3 after the welding operation. 75

Figure 5 is a similar view illustrating a modified method of welding.

Figure 6 is an end elevation of a slightly modified construction of fan wheel.

Figure 7 is a longitudinal sectional view 80 of the construction illustrated in Figure 6.

Figures 8 and 9 are detailed views of one of the complete blades of the construction illustrated in Figures 1 to 4, inclusive.

Figures 10 and 11 are detailed views of 85 one of the blade blanks.

Figure 12 is a side elevation of the welding electrodes and the supporting means for the fan wheel parts.

While in the drawings I have illustrated 90 two specific embodiments of the invention, it will of course be understood that minor changes and variations in the particular constructions shown and the carrying out of the invention in other forms as will appeal to 95 those skilled in the art and falling within the scope of the appended claims, may be practiced without departing from the spirit of the invention.

Referring to Figs. 1 to 4, inclusive, the 100 structure shown comprises end plates or disks A, B, and blades C rigidly secured at opposite ends to the end plates. The end plates A, B, which are circular in form and open at the center, in the form of rings, are 105 provided with outwardly extending lateral reinforcing flanges, the plate A having two of such flanges a, a' at its inner and outer marginal portions, and the end plate B hav- 110 ing one of such flanges b at its outer mar-

ginal part. At its inner marginal portion the blade B has an inward attaching extension b' .

The improved means and method of the present invention for securing the parts together is as follows:

The blades C are provided with tenons or integral projecting portions c, and the end plates A, B are provided with series of apertures a^2 , b^2 around the same to receive the projecting portions c of the blades. The tenons or integral projecting portions c are initially slightly smaller than the size of the apertures a^2 , b^2 , and when the parts are assembled extend through the apertures a^2 , b^2 in the plates, as indicated in Fig. 3 of the drawings. The tenons or integral projecting portions c of the blades are subjected simultaneously to heat through the medium of an electric current, and pressure, to melt down the outer end portions thereof, and to press the metal inwardly to fill up the initial space between the tenons or integral projecting portions c and the aperture wall, and to weld the parts together, the structure after the welding operation being shown in Figs. 2 and 4 of the drawings, the tenons or integral projecting portions c being of sufficient length to provide the metal necessary to fill up the initial space between the parts and make the joint shown. In the manufacture of the particular construction illustrated in the drawings the blades and end plates assembled are supported by a clamp comprising members K, K', or other suitable means, the projecting portion or portions C of the blades extending through the apertures a^2 , b^2 in the plates spaced from the walls of the apertures as indicated in Figure 3 of the drawings. An electric welder is provided having a pair of electrodes M, M', one of which is movable relatively to the other, the electrodes being adapted to be brought together to contact with the projecting ends of one of the blades and apply pressure thereto simultaneously with the application of heat. The fan wheel parts clamped together in assembled relation are supported to position one of the blades between the electrodes (see Figure 12 of the drawings). One end of the blade is placed in contact with one of the electrodes of the welder, and the other electrode is moved down on to the other projecting end portion of the blade. Simultaneously with the contact of the movable electrode with the end of the blade, the current is turned on, the ends of the blades become heated almost white hot and welded to the end plates, the projecting end portions of the blades being melted down and under the pressure of the electrodes, filling up the intervening spaces.

The blades C are blanked from sheet steel or other sheet metal, as indicated in Figs. 10 and 11 of the drawings, the blades

being afterwards curved as shown in Figs. 8 and 9 of the drawings.

It will be understood that the number of the tenons or integral projecting portions c for each blade may be varied to suit the different conditions, one of said projections being sufficient in some instances.

In Fig. 5 of the drawings is illustrated another method of welding the parts. This consists of filling the spaces between the tenons or integral projecting portions of the blades and the apertured wall with "thermite" or the like, and by the application of heat melting the same to weld the parts together.

The modified construction illustrated in Figs. 6 and 7 of the drawings is the same as that shown in Figs. 1 to 4, inclusive except that the end plates F, G are shown plain, without reinforcing flanges, the fan structure being somewhat smaller, and the extension g of plate G is shown larger.

As will be understood, the end plates and blades are adapted to be cheaply produced from stock materials by stamping, pressing or analogous methods, the openings in the plates being formed by punching.

By the special construction and arrangement of parts hereinbefore described, a simple, light structure is afforded that possesses great strength and rigidity, and one that can be produced at low cost. The special method and means for securing the parts results in a more efficient joining of the parts together, substantially an integral structure being provided, and greatly lessens the cost of production. The riveting process as commonly followed in the art is dispensed with, the assembling and connection of the parts may be more easily and better accomplished, the welding operation facilitated, and a strong, smoothly finished product and perfectly true wheel produced.

What I claim is:—

1. In a fan wheel, a blade supporting member and blade, the blade being provided at one end with an integral projecting portion of reduced size, and the blade supporting member having an aperture to receive the projecting end portion of the blade, the main end portion of the blade bearing against a face of the blade supporting member with the adjoining projecting end portion of the blade extending into the aperture of the blade supporting member and being electrically welded thereto.

2. In a fan wheel, a blade-supporting member and blade, the blade being provided at one end with an integral projecting portion, and the blade supporting member with an aperture to receive the projecting end portion of the blade, the projecting end portion of the blade initially being of a

size in cross section less than the size of the aperture and extending through the aperture, the projecting end portion of the blade being melted and pressed inwardly, and the metal of the separate parts combined by electric welding.

3. A fan wheel comprising end plates and blades rigidly secured at opposite ends thereto, each blade at each end having an integral projecting portion of reduced size, and the end plates being provided with openings to receive the projecting end portions of the blades, the main end portions of the blades bearing against side faces of the end plates, and said projecting end portions of the blades extending through the openings in the end plates and being electrically welded thereto.

4. The process of securing fan blades to end plates or rims consisting in providing a projecting portion on the end of the blade, and an aperture in the end plate or rim to receive the projecting end portion of the blade, forming the aperture of greater area than the initial cross sectional size of the projecting portion of the blade, and forming the projecting portion of the blade initially of a length to provide a mass of metal beyond the outer face of the end plate or rim, supporting the blade in position relatively to the end plate or rim with said projecting portion of the blade extending through the aperture of the end plate or rim; and simultaneously applying heat and pressure to the projecting end portion of the blade to melt down the projecting end portion of the blade to fill up the space between said end portion of the blade and the wall of the aperture, and weld the adjoining parts together.

5. The process of securing fan blades to end plates or rims, consisting in providing a projecting portion on the end of the blade, and an aperture in the end plate or rim to receive the projecting portion of the blade; forming the aperture of greater area than the initial cross sectional size of the projecting portion of the blade, and forming the projecting portion of the blade initially of a length to provide a mass of metal beyond the outer face of the end plate or rim; supporting the blade in position relatively to the end plate or rim with said projecting end portion of the blade extending through the aperture of the end plate or rim, and simultaneously subjecting the projecting portion of the blade to heat through the medium of an electric current, and applying pressure thereto to melt down the projecting end portion of the blade to fill up the space between said end portion of the blade and the wall of the aperture, and weld the adjoining parts together.

6. The process of securing fan blades to end plates or rims consisting in providing

a projecting portion on the end of the blade, and an aperture in the end plate or rim to receive the projecting end portion of the blade, forming the aperture of greater area than the initial cross sectional size of the projecting portion of the blade, and forming the projecting portion of the blade initially of a length to provide a mass of metal beyond the outer face of the end plate or rim, supporting the blade in position relatively to the end plate or rim with said projecting portion of the blade extending through the aperture of the end plate or rim; and simultaneously applying heat and pressure to the projecting end portion of the blade and the end plate portion immediately surrounding the aperture to melt down the projecting end portion of the blade to fill up the space between said end portion of the blade and the wall of the aperture, and weld the adjoining parts together.

7. The process of securing fan blades to end plates or rims consisting in providing a projecting portion on the end of the blade, and an aperture in the end plate or rim to receive the projecting portion on the blade, forming the aperture of the same shape and of slightly greater area than the initial cross sectional shape of the projecting end portion of the blade, and forming the projecting portion of the blade initially of a length to provide a mass of metal beyond the outer face of the end plate or rim, supporting the blade in position relatively to the end plate or rim with said projecting portion of the blade extending through the aperture of the end plate or rim; and simultaneously applying heat and pressure to the projecting end portion of the blade to melt down the projecting end portion of the blade to fill up the space between said end portion of the blade and the wall of the aperture, and weld the adjoining parts together.

8. The process of securing fan blades to end plates or rims consisting in providing a projecting portion on the end of the blade, and an aperture in the end plate or rim to receive the projecting end portion of the blade, forming the aperture of greater area than the initial cross sectional size of the projecting portion of the blade, and forming the projecting portion of the blade initially of a length to provide a mass of metal beyond the outer face of the end plate or rim, supporting the blade in position relatively to the end plate or rim with the projecting end portion of the blade extending through the aperture in the end plate or rim, and with the inner face of the latter in contact with the inner end face of the end plate or rim, and simultaneously applying heat and pressure to the projecting end portion of the blade to melt down the projecting end portion of the blade to fill up the space between said end portion of the blade and the wall of the aperture, and weld the adjoining parts together.

space between said end portion of the blade and the wall of the aperture and weld the adjoining parts together.

9. The process of securing fan blades to 5 end plates or rims consisting in providing a projecting portion on the end of the blade, and an aperture in the end plate or rim to receive the projecting end portion of the blade, forming the aperture of greater area 10 than the initial cross sectional size of the projecting portion of the blade, and forming the projecting portion of the blade initially of a length to provide a mass of metal beyond the outer face of the end plate of 15 rim at least substantially equal to the difference in the cross sectional size of the projecting portion of the blade and the area of the aperture, supporting the blade in position relatively to the end plate or rim 20 with said projecting portion of the blade extending through the aperture of the end plate or rim, and simultaneously applying heat and pressure to the projecting end portion of the blade to melt down the projecting end portion of the blade to fill up the space between said end portion of the blade and the wall of the aperture, and weld the adjoining parts together.

10. The process of securing fan blades to 30 end plates or rims consisting in providing a projecting portion on the end of the blade, and an aperture in the end plate or rim, forming the aperture of greater area than the initial cross sectional size of the projecting end portion of the blade, and forming each projecting end portion of the blade initially of a length to provide a mass of metal beyond the outer face of the end plate or rim, supporting the blade in position between the end plates or rims with the projecting end portion of the blade extending through the apertures of the end plates or rims, and simultaneously applying heat and pressure to the projecting end portion of 40 the blade and the end plate portion surrounding the apertures to melt down the projecting end portions of the blade to fill up the space between said end portions of the blade and the walls of the apertures, and weld the adjoining parts together.

11. The method of making fan wheels consisting in providing the blades with a projecting portion on each end of the blade, and apertures in the end plates or rims to 55 receive the projecting end portions of the blades, forming the apertures of greater area than the initial cross sectional size of the projecting portions of the blades, and forming the projecting portions of the blades initially of a length to provide a mass of metal beyond the outer faces of the end plates or rims, supporting the blades and rims in assembled position with the projecting portions of the blades extending through 60 the apertures of the end plates or rims; and

simultaneously applying heat and pressure to the projecting end portions of each blade to melt down the projecting end portions of the blade to fill up the space between said end portions of the blades and the walls of 70 the apertures, and weld the adjoining parts together.

12. The method of making fan wheels consisting in providing the blades with a projecting portion on each end of the blade, and apertures in the end plates or rims to receive the projecting end portions of the blades, forming the apertures of greater area than the initial cross sectional size of the projecting portions of the blades, and forming the projecting portions of the blades initially of a length to provide masses of metal beyond the outer faces of the end plates or rims, supporting the blades and rims in assembled position with the projecting portions of the blades extending through the apertures of the end plates or rims, and simultaneously subjecting the projecting end portions of each blade to heat through the medium of an electric current and applying pressure thereto to melt down the projecting end portions of the blade to fill up the space between said end portions of the blade and the walls of the apertures, and weld the adjoining parts together.

13. The method of making fan wheels consisting in providing the blades with a projecting portion on each end of the blade, and apertures in the end plates or rims to receive the projecting end portions of the blades, forming the apertures of greater area than the initial cross sectional size of the projecting portions of the blades, and forming the projecting portions of the blades initially of a length to provide masses of metal beyond the outer faces of the end plates or rims, supporting the blades and rims in assembled position with the projecting portions of the blades extending through the apertures of the end plates or rims and simultaneously subjecting the projecting end portions of each blade to heat and pressure by a pair of combined electrodes and pressing members operating simultaneously upon the opposite ends of the blade.

14. The method of making fan wheels consisting in providing the blades with a projecting portion on each end thereof, and apertures in the end plates or rims to receive the projecting end portions of the blades, forming the apertures of greater area than the initial cross sectional size of the projecting portions of the blade, and forming the projecting portions of the blade initially of a length to provide masses of metal beyond the outer faces of the end plates or rims supporting the blades and rims held together in assembled position with the projecting portions of the blades extending through the apertures in the end 125

- plates, and the latter in contact with the end faces of the blades, and then simultaneously applying heat and pressure to the projecting end portions of each blade and the end plate portions surrounding the apertures to melt down said projecting end portions of the blade to fill up the spaces between the projecting end portions of the blade and the walls of the apertures, and weld the adjoining parts together. 35
15. The method of making fan wheels consisting in providing the blades with a projecting portion on each end thereof, and apertures in the end plates or rims to receive the projecting end portions of the blades, forming the apertures of greater area than the initial cross sectional size of the projecting portions of the blade, and forming the projecting portions of the blade 40 initially of a length to provide masses of metal beyond the outer faces of the end plates or rims, supporting the blades and rims held tightly together in assembled position with the projecting portions of the blades extending through the apertures in the end plates, and the latter in contact with the end faces of the blades, and then simultaneously applying heat and pressure to the projecting 45 end portions of each blade, and the end plate portions surrounding the apertures to melt down said projecting end portions of the blade to fill up the space between the projecting end portions of the blade and the walls of the apertures, and weld the adjoining parts together. 50
- 20
- 25
- 30

16. The method of making fan wheels consisting in providing the blades with a projecting portion on each end thereof, and apertures in the end plates or rims to receive the projecting end portions of the blades, forming the apertures of slightly greater area and of the same shape as the initial cross sectional shape and size of the projecting portions of the blade, and forming the projecting portions of the blade initially of a length to provide masses of metal beyond the outer faces of the end plates or rims, supporting the blades and rims held tightly together in assembled position with the projecting portions of the blades extending through the apertures in the end plates, and the latter in contact with the end faces of the blades, and then simultaneously applying heat and pressure to the 55 projecting end portions of each blade, and the end plate portions surrounding the apertures to melt down said projecting end portions of the blade to fill up the space between the projecting end portions of the blade and the walls of the apertures, and weld the adjoining parts together. 60

In testimony whereof I hereunto affix my signature in the presence of two witnesses.
